UNITED STATES PATENT OFFICE

DAVID H. EBINGER, OF COLUMBUS, OHIO, ASSIGNOR TO THE D. A. EBINGER SANITARY MFG. COMPANY, OF COLUMBUS, OHIO, A CORPORATION OF OHIO

WASTE PIPE FITTING

Application filed July 23, 1931. Serial No. 552,648.

This invention relates to waste pipe fittings and more particularly to that type of fittings adapted for use in connection with sinks and similar fixtures and wherein the fitting not only constitutes a coupling for connecting the sink to a waste pipe or drain conduit, but also provides in connection therewith a stopper or valve member movable within the coupling or fitting from seated to unseated positions.

It is also an object of the present invention to incorporate in such a fitting novel means for effecting the raising and holding of the valve or stopper member in an unseated position so that the liquid may have a full passage through said fitting and into the waste line.

Another object of the invention is to provide in connection with a fitting of this character a strainer member in the form of a basket which may be removed for emptying or cleaning purposes without effecting the actuation of the stopper member.

The stopper member in turn may also be operated from a closed to an open position without interfering with the basket or strainer member.

A further object of the invention is to provide a sink with an outlet opening having an angular downwardly projecting neck in the shape of a funnel located below said outlet and which neck or funnel is of such size as to accommodate the basket positioning the same so that its upper end is below the upper surface of the sink bottom and thereby causing the water to flow into the basket through the open top thereof with the particles of foreign matter therein, which will thus be collected in the basket or strainer member.

With these and other objects in view, which will appear as the description proceeds, the invention consists in the novel features of construction, combinations of elements and arrangement of parts hereinafter to be more fully described and pointed out in the appended claims.

In the accompanying drawings:

Figure 1 is a vertical sectional view taken through a portion of the sink and the waste

pipe fitting comprising the present invention,

Figure 2 is a top plan view thereof,

Figure 3 is a horizontal sectional view taken on the line 3—3 of Figure 1,

Figure 4 is a detail enlarged vertical sectional view showing more in detail the means for retaining the stopper member in its elevated position.

Referring more particularly to the drawings the numeral 1 designates the sink formed with the usual outlet in the bottom 2 thereof. Formed integrally with the bottom 2 and located around the outlet is an angular downwardly projecting neck or funnel shaped extension 3 and arranged in alignment therewith and extending downwardly therefrom is a waste pipe 4. This pipe has its upper end flared and enlarged as at 5, and formed with an outwardly extending flange 6 between which and the lower end of the neck extension 3 is positioned a suitable gasket 7. The waste pipe is internally threaded for the reception of a similarly threaded lower end of a fitting 8 which constitutes the coupling between the waste pipe 4 and the sink 1 and to which the present invention is particularly directed.

The fitting 8 is in the form of a sleeve and has its upper portion enlarged as at 9 and positioned within the extension 3 so as to bear against the inner surface thereof. In connecting the waste pipe to the sink the fitting 8 is inserted downwardly through the extension 3 and into the upper end of the waste pipe threaded thereinto, drawing the flange 6 tightly against the gasket 7 with the enlargement 9 bearing against the inner surface of the extension 3 a distance above the lowermost end thereof. In a general way this construction is commonly employed for attaching the waste pipe to sinks, wash bowls, or the like.

Positioned for vertical movement within the fitting 8 is a valve or stopper member 10 formed to include a tapered head 11 adapted for normal engagement with the similarly tapered seat 12 formed interiorly of the fitting 8 and at the lower end thereof. Arising centrally from the head 11 is a stem 13 which

has an intermediate portion received within an opening formed in a strainer plate 14 rigidly secured to the enlargement 9 by means of screws or other fastening elements 15. 5 The plate 14 serves to guide the stopper member in a vertical movement from a closing to an opening position. To retain the stopper member in its elevated position, there is provided on the under side of the plate 14 a circular body 16 having a reduced extension 17 positioned through the central opening formed in the plate 14 peened over, riveting the same to the plate member. Formed in the member 16 is a pair of diametrically opposed bores 18 in which are positioned balls 19 which are resiliently held against the stem 13 by means of springs 20 confined within the bores 18 by means of a band 21 surrounding the body 16. The springs 20 which are held compressed 20 within the bores will cause the balls 19 to move inwardly towards each other upon the raising of the valve or stopper member and position themselves under a shoulder 22 formed by reducing the stem 13 at its lower 25 end thereby holding the stopper in its elevated position as disclosed by dotted lines in Figure 1. In order to manipulate the stopper member the stem 13 has its upper end reduced as at 23 forming a knob 24 providing 30 a finger hold. This construction of the stopper member and the retaining means therefor permits the stopper member to be rotated axially and may be held seated or unseated in any revoluble position within the coupling 35 or fitting in contrast to many ordinary constructions wherein it is necessary to seat the stopper in a predetermined position or one of a number of predetermined positions in order to effect the movement thereof to seat and 40 unseat the stopper, and, moreover, to turn the stopper to a predetermined position of a revolution when raised to a position in which the stopper is unseated in order to maintain the stopper in this position. The present 45 construction overcomes this precision in placing parts and will hold the stopper member in either its raised or lowered position by simply manipulating the latter in a straight vertical plane.

50 Positioned above the plate 14 and within the funnel shaped extension 3 is a strainer dish or basket 25 which is of considerable depth and has its upper edge 26 arranged slightly below the upper surface 27 of the 55 sink bottom. The circular side wall of the basket 25 is formed to snugly fit and conform to the tapered inner wall of the extension 3 to form a tight joint therebetween and prevent any particles of foreign matter from 60 passing therethrough but will flow into the basket and out through the fitting into the waste pipe collecting any such articles of foreign matter which are too large to pass through the perforations in the basket. In 65 order to effect the removal of the basket from

its engagement within the sink a handle 28 is provided centrally of the basket and is so shaped as to have a portion on each side of the stem 13. The handle clip 28 is also provided with an opening through which the 70 stem 13 extends by which the basket is guided when positioned within the extension 3 of the sink. It will be noted that the basket may be seated in any rotatable position within the sink body and upon the stem 13 and 75 that the same does not interfere with the actuation of the stopper member, the operating portions of the handle clip 28 being so spaced that access may be had to the stem 13 therebetween.

It will be apparent from the foregoing that a waste pipe fitting construction has been provided with a stopper member and a strainer basket is associated therewith which may be operated independently of one another. Either the strainer basket or the stopper member may be turned or seated in any position. The stopper may be opened by merely raising up on the stem and held in its raised position by the resilient action of the 80 spring pressed balls. The balls in no way interfere with the revolving of the stopper in order to form a better seat as, for example, by crushing or grinding particles of matter which may adhere to the tapered face of the 85 stopper, or to its seat, or for other purposes. The fitting is extremely simple in its construction, efficient in its operation, reliable and comparatively economical and simple to manufacture.

What is claimed is:

1. A waste pipe fitting adapted to be positioned within an outlet neck formed in the bottom of a sink or the like, said fitting comprising an open ended sleeve-like body 100 threaded at its lower end and serving to connect a waste pipe to said outlet neck, a seat formed with the lower end of said fitting, a stopper member engageable with said seat and having an operating stem projecting upwardly therefrom, a perforated plate secured to the upper end of said fitting having an opening for the reception of said stem, spring pressed members mounted on the under side of said plate and engaging said stem, and a shoulder formed on the lower portion of said stem and adapted for engagement with said spring pressed members to hold the stopper member in an elevated position away from said seat.

2. A waste pipe fitting adapted to be positioned within an outlet neck formed in the bottom of a sink or the like said fitting comprising an open ended tubular body enlarged at its upper end to engage the inner surface 110 of said outlet neck and threaded at its lower end for the connection of a waste pipe to said neck, a stopper member movable within said fitting to and from a seat formed therein at the lower end of the fitting, an operating 115

- stem for said stopper projecting upwardly therefrom, a strainer basket positioned within said outlet neck having an opening for the reception of said stem, and a handle clip for the said basket having an operating portion positioned on each side of said stem, said stem serving as a guide for said basket during the positioning of the same within said neck portion.
- 10 3. A waste pipe fitting adapted to be positioned within a funnel shaped outlet neck formed in the bottom of a sink or the like, said fitting comprising an open ended tubular body member enlarged at its upper end and adapted to bear against the inner surface of said outlet neck, said tubular body being threaded at its lower end for connection with a similarly threaded upper end of a waste pipe for its connection to said outlet neck, a
- 15 perforated plate secured to the upper end of said body, a seat formed in the lower end of the tubular body, a vertically movable stopper member within said fitting engageable with said seat and having an operating
- 20 stem extending through a centrally located opening formed in said perforated plate, yieldable means on the under side of said plate and engaging said stem to hold the stopper in an elevated position away from
- 25 said seat, a strainer basket removably positioned within the upper portion of said outlet neck and having an opening for the reception of said stem, and a U-shaped handle clip attached to the central portion of said basket
- 30 and through which said stem extends, said U-shaped clip serving to confine the upper end of said stem when said stopper is in engagement with said seat.
- 35

In testimony whereof I affix my signature.

40 DAVID H. EBINGER.
